UNITED STATES PATENT OFFICE.

CHARLES EDWARD LITTLE, OF LONDON, ENGLAND, ASSIGNOR TO S.
MORDAN & COMPANY, OF SAME PLACE.

PENCIL-CASE.

SPECIFICATION forming part of Letters Patent No. 331,896, dated December 8, 1885.

Application filed June 4, 1885. Serial No. 167,602. (No model.) Patented in England February 17, 1885, No. 2,204, and in Germany February 26, 1885, No. 32,734.

To all whom it may concern:

Be it known that I, CHARLES EDWARD LITTLE, a subject of the Queen of Great Britain and Ireland, residing at London, England, 5 silversmith, have invented new and useful Improvements in Pencil-Cases, of which the following is a specification.

Heretofore it has been general to construct pencil-cases in such a manner that when a lead 10 is expended or used up it becomes necessary to refill the case with a lead taken either from an independent box, or to unscrew the bottom of the pencil-case to withdraw a lead from the receptacle containing the same, and then to 15 unscrew the "point" or nozzle in order to introduce such lead. This has necessitated time and trouble and handling of the leads, which, being brittle and slender, were liable to break in filling.

Now, the object of my invention is to avoid 20 these evils, and to construct pencil-cases in such a manner (as hereinafter fully described) that the leads are contained in a magazine or holder provided around the upper part of the pencil-case and forming part thereof, and are 25 fed continuously to the point or nozzle of the instrument by simply turning the hinder or lower part of the said pencil-case, and without having to remove the point or nozzle.

My invention will be readily understood on 30 reference to the accompanying drawings, in which--

Figure 1 is an elevation of a pencil-case constructed according to my invention, and shown full size. Fig. 2 is a longitudinal section of the pencil-case complete in all its parts. Fig. 3 is a cross-section, on line *x* *x* of Fig. 2, of the magazine or holder. Fig. 4 is a 35 separate view of the propelling mechanism and feeding-tube. Fig. 5 is a section on line *y* *y* of the semicircular feeder, the arrow showing the direction of motion. Fig. 6 is a detached view of the feeding and propelling tube.

The figures from 2 to 6, both inclusive, are 40 shown on an enlarged scale for sake of clearness.

In carrying out my invention I combine with the ordinary "spiral action Z," (or with

any like suitable movement,) which needs no 50 detailed description, but which is used for propelling and projecting the lead beyond the point or nozzle, a tube, *a*, which surrounds and is concentric with a central tube, *b*, through and along which travels the ejector 55 or pin *c*, employed for projecting outward the lead. This tube *a* forms the magazine or holder for the leads *l*, which lie in the space existing between said tubes *a* and *b*. These leads are placed in the interior of the pencil-case, and lie around the central tube, *b*, as seen in cross-section, Fig. 3. They are retained in position by resting on the annular block or ring *A*, and against the interior wall of the tube *a*. 65

The central tube, *b*, is of special construction. It is furnished with a slot or opening, *d*, slightly exceeding the length of the leads, and this slot is provided with a suitably-shaped lip or strip of metal, *e*, which forms and acts as a 70 scoop; or the tube may be provided with arms or pins answering the same purpose. This scoop (or these arms) on the tube *b*, being revolved to the left when the ejector *c* is completely withdrawn into the spiral action, 75 takes or scoops up one lead in its revolution and deposits it into the slot or opening *d*, through which it falls into the tube and onto the top end of the ejector, where it is then ready for being projected outward on the 80 ejector being operated by turning or revolving the hinder part of the pencil-case to the right. The upper part of the central tube is screw-threaded, and receives the "nozzle" or point of the pencil, as seen in Fig. 2. The 85 tube or magazine *a* is held in place by frictional contact with the tube or block *g*, which is secured to the tube *b*, and around this tube the ring *p* is soldered. The purpose of this ring *p* is to prevent the magazine or holder 90 being drawn off backward. The lower or hinder portion of the pencil-case is secured to the "action" in the usual manner. An indicating-mark, *f*, which may be an arrow, as shown in Fig. 1, is engraved or stamped on 95 the nozzle, so that in actuating the pencil it may be at once known that after the complete rotation of the nozzle to the left a fresh lead

has been scooped up and has fallen into the slot or opening in the central tube.

The method of working is as follows: The magazine being filled with leads, and the 5 ejector assumed to be at its lowermost point, I revolve the hinder part of the pencil-case to the left, thereby causing the central tube, with its scoop or equivalent, to revolve, or 10 partially revolve, as may be necessary, at the same time and to the same extent, and to take or scoop up a lead in its revolution and to feed the same to the interior of the central tube. I then revolve the hinder part of the pencil-case to the right, thereby bringing the ejector 15 into action, whose office it is to project the lead into and slightly beyond the nozzle, for use in the ordinary manner. When the lead is expended, the ejector is withdrawn completely into the spiral action by winding it 20 downward to the left, and by continuing this winding the central tube is revolved, or partially revolved, and in its movement the scoop takes up another lead and deposits it into the interior of said central tube. The 25 winding action is then reversed, and the ejector, coming into action again, projects the lead outward, as above mentioned. These winding movements are renewed as often as required, until the leads in the magazine are 30 used up, when the nozzle or point is un-

screwed and the magazine refilled with a fresh charge of leads.

This invention was patented in Great Britain February 17, 1885, No. 2,204, and in the German Empire February 26, 1885, No. 32,734. 35

Having now described my invention, what I claim, and desire to secure by Letters Patent, is—

1. The combination, with the spiral action and the ejector receiving motion from the 40 same, of a tube through which the ejector passes, having a slot and scoop at one side, a magazine or holder surrounding the slotted tube, for containing leads, and a pencil case and point, substantially as specified. 45

2. In combination with the propelling-action of a pencil-case, a magazine or holder, and a slotted lead-tube provided with a scoop or equivalent device, the whole arranged as herein described and shown, and operating as 50 set forth.

In witness whereof I have hereunto signed my name in the presence of two subscribing witnesses.

CHARLES EDWARD LITTLE.
